COMBINED FASTENER AND HANGER

Herbert E. Stout, Weehawken, N. J.

Application August 10, 1933, Serial No. 684,588

2 Claims. (Cl. 40—145.1)

This invention relates to a combined fastener and hanger for picture frames and the like, the general object of the invention being to provide a number of brackets attached to the rear part of the frame and each having an angle-shaped member pivoted thereto, one arm of which acts to hold a backing member in the frame and the other arm having a hole therein for receiving the picture cord or other flexible member.

10 This invention also consists in certain other features of construction and in the combination and arrangement of the several parts, to be herein-after fully described, illustrated in the accompanying drawing and specifically pointed out in the appended claims.

15 In describing the invention in detail, reference will be had to the accompanying drawing wherein like characters denote like or corresponding parts throughout the several views, and in which:

Figure 1 is a rear view of a picture frame, showing four of the devices carried thereby.

Figure 2 is a section on line 2—2 of Figure 1.

25 Figure 3 is a perspective view of one of the angle-shaped members.

Figure 4 is a perspective view of one of the brackets.

In this drawing, the letter A indicates a frame for a picture or the like and the letter a indicates the backing member. In carrying out my invention, I provide a plurality of brackets 1 which are attached to different parts of the rear portion of the frame A, as shown in Figure 1. Each bracket has pivoted thereto an angle member 2, the pivot pin being shown at 3. The pivot pin passes through a hole 4 in one end of the angle member.

30 The angle member consists of a long arm 2' and a short arm 2'', these arms being arranged in a V, with the short arm bent upwardly or rearwardly and the free end of the arm 2' having a bent-up part to form a finger hold 5.

I prefer to arrange four of these devices on the rear of the frame, as shown in Figure 1, so that the frame can be hung in a vertical position, as 45 shown in Figure 1, by attaching the cord a' to the short arms of the members which are attached to the side members of the frame or in a horizontal position by attaching the cord a' to the other pair of devices shown in Figure 1. As before 50 stated, the long arms, extending over the backing member, will hold this member, the picture or other member 6 and the glass 7 in the frame, as shown in Figure 2, and when these parts are 55 to be removed, it is simply necessary to swing the members to a position outwardly of the frame so

that the long arms will not engage the backing member and thus the parts can be removed. As before stated, the projection 5 acts as a finger hold for facilitating the swinging of the devices. If the long arms 2 of the devices engage the backing member with sufficient friction, as they usually do, the devices will remain in the position in which they are placed by hand, due to this friction, but if the weight of the picture frame is greater than this friction, then the two devices 60 to which the cord is attached will swing on their pivots 3 to positions where the short arms will align with the cord.

65 It is thought from the foregoing description that the advantages and novel features of the invention will be readily apparent.

70 It is to be understood that changes may be made in the construction and in the combination and arrangement of the several parts, provided that such changes fall within the scope of the appended 75 claims.

What is claimed is:—

1. In combination with a frame member and a member supported therein, a number of brackets fastened to the rear part of the frame member, a 80 V-shaped member pivoted to each bracket and having one arm longer than the other, the long arm extending across the member in the frame to hold the said member in the frame, the short arm having a hole therein for receiving hanging 85 cord.

2. In combination with a frame member and a member supported therein, a number of substantially V-shaped members pivotally supported from the rear part of the frame member, each 90 member having one arm longer than the other, the long arm extending across the member in the frame to hold said member in the frame, the short arm having a hole therein for receiving a hanging 95 cord.
